(57) **CLAIM**

The ornamental design for a combination sleeping bag and backpack, as shown and described.

DESCRIPTION

FIG. 1 is a top, front, right side perspective view of the combination sleeping bag and backpack, showing my new design;

FIG. 2 top plan view thereof;

FIG. 3 is a front elevational view thereof;

FIG. 4 is a right side elevational view thereof;

FIG. 5 is a left side elevational view thereof;

FIG. 6 is a rear elevational view thereof;

FIG. 7 is a top, front, right side perspective view of the combination sleeping bag and backpack, shown in the opened condition;

FIG. 8 top plan view thereof;

FIG. 9 is a front elevational view thereof;

FIG. 10 is a right side elevational view thereof;

FIG. 11 is a left side elevational view thereof; and,

FIG. 12 is a rear elevational view thereof.

The dash-dash-dash broken lines shown in the drawings represent stitching lines.

The dot-dot-dash broken lines shown in the drawings are for illustrative purposes only and form no part of the claimed design.
